COMBINATION PENCIL CLIP AND SHARPENER

Gustaf W. Nyberg and Charles Johnson,
Chicago, Ill.

Application May 11, 1940, Serial No. 334,480

17 Claims.

(Cl. 120—84)

This invention relates to an improved combination pencil clip and sharpener.

A general object of the invention is to provide an improved device for use with an ordinary lead pencil and adapted to serve not only as a clip for holding the pencil in the user's pocket, but also as means for sharpening the pencil to a tapered writing point.

A further object is to provide a combined pencil clip and sharpener having a novel construction adapting it for economical quantity manufacture, and having but few and easily made parts which can be readily assembled.

Another object is to provide a novel clip and sharpener which is inexpensive and which is efficient in use.

Another object is to provide a device of this character which is adapted while in use as a clip to be conveniently released in order to facilitate clipping onto or removal from a coat pocket and to facilitate longitudinal adjustment on the pencil.

Still another object of the invention is to provide a combination pencil clip and sharpener in which all of the parts are held together permanently by a novel arrangement of clamping or securing lugs or flanges formed on one of the parts.

A further object is to provide an improved arrangement in such a device for smooth, uniform sharpening of the pencil.

Other objects and advantages will become apparent in the following description and from the accompanying drawing in which:

Figure 1 is a side elevational view of a device embodying the invention showing its use as a pencil clip.

Fig. 2 is an opposite side elevational view partially broken away for clarity, showing the clip in released position on the pencil.

Fig. 3 is a side elevational view of the device showing it in use as a pencil sharpener.

Fig. 4 is an outer face view of the device.

Fig. 5 is an inner face view of the device.

Fig. 6 is an enlarged longitudinal sectional view through the device.

Fig. 7 is a transverse sectional detail view taken substantially along line 7—7 of Fig. 6.

Fig. 8 is a sectional detail view taken substantially along the transverse line 8—8 of Fig. 6.

Fig. 9 is a sectional detail view taken in the plane of line 9—9 of Fig. 6.

Fig. 10 is an exploded assembly view of the device.

While the invention is susceptible of various

modifications and alternative constructions, we have shown in the drawing and will herein describe in detail a preferred embodiment, but it is to be understood that we do not thereby intend to limit the invention to the specific form disclosed but intend to cover all modifications and alternative constructions falling within the spirit and scope of the invention as expressed in the appended claims.

As shown by way of example in the drawing, a preferred form of the device comprises but three separately manufactured elongated elements including a body member 15 serving as a base to which are secured a resilient retaining member or spring 16 and a flat knife member or blade 17. Each of the three elements of the device is fashioned to enable formation thereof as a die stamping, and the relationship of the elements one to the other is such that they may be quickly and easily assembled. A simple arrangement of bent over flanges and lugs on the body member 15 holds the elements securely together in a permanent unit. The device may serve either as a pencil clip (Fig. 1) wherein the retaining spring 16 serves to hold the device adjustably in place upon a pencil 18, or as a pencil sharpener (Fig. 3) wherein one end of the retaining spring 16 stands away from the body member to form therewith a socket adapted to receive and properly locate the point of the pencil 18 relative to the knife blade 17 during sharpening.

In the present instance, the body member 15 is formed in a generally tapered elongated shape (Figs. 4 and 10), and is provided with means comprising a pair of opposed arms 19 for embracing the body of the pencil 18. The arms 19 may conveniently be formed as integral wing projections from the respective opposite longitudinal margins of the body member, and are preferably curved slightly inwardly at their extremities (Fig. 5) to conform generally to the shape of the pencil. The length of the arms 19 is preferably such that, with the curved ends in embracing engagement with the pencil, the inner face of the body member 15 is spaced from the pencil 18. The spring member 16 is disposed within this space, and acts to press the pencil into engagement with the curved extremities of the arms 19.

The point at which the spring 16 presses against the pencil is preferably opposite the free wide end portion of the body member 15, and hence there is a tendency for the narrow end portion of the body member to pivot inwardly

toward the pencil so as to grip the coat pocket, indicated at 20. Preferably the narrow end portion of the body member 15 is inclined slightly inwardly as shown at 21, and is formed with an inwardly projecting rounded nib 22.

The spring member 16 herein comprises a leaf spring generally similar in marginal outline to the body member 15, and secured at one end flatwise against the latter for flexure at its free other end between the pencil-embracing arms 19. The fixed end portion 23 of the spring 16 is substantially flat and rectangular in shape, and is snugly confined in juxtaposition to the angular nib portion 21 between opposed inwardly projecting marginal flanges 24 on opposite sides of the body member 15. Two clamping lugs or ears 25 projecting from the flanges 24 are bent or struck over the spring end portion 23 to secure the body member 15 and the spring 16 in rigid permanent assembly. The free end portion of the spring 16 extends along the body member 15 and freely between the arms 19 and normally assumes a relative divergent position as shown in Figs. 3 and 6. Consequently, the spring 16 is free to flex between the arms 19 toward and from the body member 15. When the pencil 18 is inserted between the arms 19, the spring 16 is flexed inwardly toward the body member 15 (see Fig. 1) and hence is placed under a deflection tension, tending to urge the nib 22 into clamping position. The spring 16 is formed at its free extremity with a curved rest 27 seating against and conforming generally to the transverse shape of one side of the pencil 18.

Intermediate its ends the spring member 16 is bowed transversely to provide a rounded projection 28 adapted for engagement with the pencil 18. By pressing the free outer end of the body member 15 toward the pencil as shown in Fig. 2, the projection 28 will be caused to engage the latter, and the anchored end of the spring 16 will be flexed outwardly to lift the nib 22 to effect release of the arms 19 from binding engagement. This permits the fabric of the coat pocket 20 to be inserted between the pencil and the nib 22, and also facilitates adjustment of the clip along the pencil.

To use the device as a pencil sharpener, it is removed from the pencil 18, and the point of the pencil is inserted into the flaring socket defined between the body member 15 and the spring 16 (Figs. 3 and 6). This brings the pencil point into engagement with the knife blade 17 which is secured flatwise against the inside face of the body member. As shown (Figs. 6 and 10), the knife blade 17 is preferably of a length to extend from the angular nib-carrying portion 21 of the body member to a point beyond the pencil-engaging arms 19, and has an end section 29 interposed between the fixed end 23 of the spring 16 and the body member 15, and hence also secured in position by the clamping ears 25 (Fig. 9). The back edge of the knife blade 17, herein the right hand edge when viewed from the inside of the clip as in Fig. 5, abuts the adjacent marginal flange 24, and is further held in position by a series of spaced lugs 30 and 31.

Throughout the major portion of its length, the blade member 17 is of a reduced width, and is formed with a longitudinal knife edge 32 (Figs. 7 and 10) in registry with a longitudinal slot 33 in the body member 15. The arrangement is preferably such that the shaving or sharpening action is effected by right hand rotation of the pencil in the socket.

The length of the pencil point is limited by a shoulder 34 (Figs. 6, 8 and 10) formed at the inner end of the knife edge, and disposed for end engagement by the lead as the point becomes progressively longer in the course of sharpening. Shavings from the pencil point may escape freely through the slot 33 and also through a slot 35 provided for this purpose in the overlying portion of the spring member 16 (Figs. 5, 8 and 10). At the inner end of the slot 35 the spring member 16 is formed with an outwardly pressed longitudinal rib 36 (Figs. 3, 6 and 10) which defines a narrow internal groove adapted to receive the sharpened lead tip of the pencil but to provide ample clearance therefor so as to avoid binding or jamming and breaking of the tip.

To assure smooth, uniform shaving during sharpening, means is provided for properly supporting and centering the tapered pencil point relative to the knife edge 32. As best seen in Figs. 7 and 10, such means may include a gauging flange 37 determinative of the angle of approach of the pencil point surface and the knife edge 32. This flange 37 is preferably formed integrally with the body member 15 to project from the inner face thereof longitudinally along the margin of the slot 33 opposite the knife edge 32 and approximately in the plane of the edge. Lateral support for the pencil point adjacent to the gauging flange 37 is provided by a curled over lug 38 formed integral with the adjacent marginal flange 24. In addition, the inner face of the spring member 16 by reason of its lateral curvature to form the lug 28 is generally concave where it is engaged by the pencil point so as to function in cooperation with the gauging flange 37 and the supporting lug 38 in centering and supporting the pencil point with respect to the knife edge.

Endwise pressure applied to the pencil point section during sharpening has a tendency to force the body member 15 and the spring member 16 apart due to the yieldable character of the spring member. Means establishing a positive limit upon such separation is therefore provided preferably at the opposite ends of the yieldable section of the spring member. Adjacent to the attached end of the spring member such means comprises a pair of movement controlling lugs 39 (Figs. 5, 6 and 8) projecting inwardly from the respective marginal flanges 24. Adjacent to the opposite end of the spring member the limiting means comprises a pair of laterally extending lugs or ears 40 upon the spring member which are adapted to engage within appropriate locking notches 41 (Figs. 3, 6 and 10) formed in the edges of the arms 19. As a result, spreading apart of the spring member and body member due to longitudinal pressure of the pencil point is confined to the limits permitted by the movement controlling lugs 39 and the interengaging locking ears 40 and notches 41.

The body 15 is formed with means to facilitate the attachment thereto of a display device 42 (Figs. 1 and 4) such, for example, as an identification badge or commercial slogan or advertising tag or button. Such a device may be attached for use at conventions and other special meetings. In the present instance, the relatively wide end portion of the body member 15 is formed with a suitably shaped and dimensioned aperture 43 adapted to receive the attachment means of the display device 42. Through this arrangement the display device 42 is supported prominently out in front when the pencil and clip assembly is clipped in place in the socket.

From the foregoing it will be apparent that the present invention provides an efficient combination pencil clip and sharpener construction which can be inexpensively manufactured by quantity production methods and sold at low cost. All of the parts are adapted to be made as die stampings, the grinding of the knife edge being the only operation other than stamping required in the formation of the parts. Assembly of the three formed parts of the device is simply and easily effected merely by alining the parts in the relative positions to be assumed in the completed device and bending over a series of pre-formed flanges or lugs which permanently connect the parts together. When in use as a pencil clip, the device holds securely upon the pencil and effectively grips the wall of the pocket within which the pencil may be lodged, but adjustment of the clip longitudinally of the pencil or release thereof from the pocket wall may be effected naturally and without resistance. As a sharpener, the device performs smoothly and uniformly to produce a neat long tapered point upon the pencil.

We claim as our invention:

1. In combination in a device of the character described, an elongated body member having a pair of opposed pencil-embracing arms at one end of said body, a spring lever located between said arms and having a free end for engaging and pressing an associated pencil against said arms, a separate knife blade member located between said spring member and said body member for sharpening the point of the pencil when the latter is removed from the device and inserted between said spring member and said body member, and means at the opposite end of said body for clamping the other end of said spring member and said knife blade permanently to said body member.

2. A pencil clip and sharpening device of the character described comprising, in combination, an elongated body member having opposite longitudinal marginal flanges, a spring lever member, a knife blade, said spring lever member and said knife blade having end portions of substantially equal width adapted to fit in assembly in superimposed relation between said flanges, and clamping wing extensions on said flanges for securing said spring lever and knife blade to said body member.

3. In combination in a device of the character described, a body member having a pair of opposed pencil-engaging arms, cutting means on said body member between said arms, a spring member secured at one end to said body member and operable when the device is used as a pencil clip to press the body of the pencil against said arms and when the device is used as a sharpener to assist in locating the pencil point in sharpening relation to said cutting means, and means adjacent to opposite ends of said spring member for limiting relative separation of the spring member and the body member due to the pressure applied to the pencil point during sharpening.

4. In combination in a device of the character described, a body member having a pair of opposed pencil-engaging arms, cutting means on said body member between said arms, a spring lever operable when the device is used as a pencil clip to press the body of the pencil against said arms and when the device is used as a sharpener to assist in locating the pencil point in sharpening relation to said cutting means, a pair of lugs

engageable with said spring lever adjacent to one end for limiting outward movement thereof under the influence of endwise pressure from the pencil point during sharpening, and a pair of ears projecting laterally from said spring lever adjacent to its opposite end engageable with said arms for limiting outward movement of the spring lever.

5. In combination in a pencil clip and sharpener device of the character described, an elongated body member including means for engaging a pencil when the device is used as a pencil clip, a cutting means on said body member, a spring lever secured at one end to said body member and adapted for assuring a gripping relationship between the pencil and said engaging means and serving also to hold the pencil point in proper relation to said cutting means when the device is used as a sharpener, and means engageable with said spring lever adjacent to the secured end thereof for limiting separating movement of said spring lever and said body member due to axial force applied to the pencil point during sharpening.

25 6. A pencil clip and sharpener device of the character described including, in combination, an elongated body member having a pair of pencil-engaging arms adjacent to one end thereof, an elongated spring lever secured at one end adjacent to the opposite end of said body member and having a free yieldable section lying between said arms to engage and yieldably press the body of an associated pencil against said arms, cutting means on said body member opposite said free section of the lever adapted for sharpening the point of the pencil when inserted between said body member and said free section, a pair of laterally projecting ears on said spring lever adjacent to the free extremity thereof, and means on said arms for engagement by said ears to limit separating movement of said body member and said spring lever.

45 7. A pencil clip and sharpener device comprising, in combination, an elongated clip body having means adjacent to one end thereof for embracing a pencil, an elongated spring lever having one end thereof secured adjacent to the opposite end of said body member and extending freely opposite said one end of the body member for cooperation with said pencil-engaging means in holding the device upon the pencil, an engagement nib at said opposite end of said body member beyond the end of said spring lever and arranged to be pressed against the body of the pencil or to grip the wall of a pocket upon which the assembled pencil and clip may be clipped, and means manipulable by the user for selectively releasing said nib from either the pencil-engaging or pocket-wall gripping relationships thereof.

55 8. In combination in a combined pencil clip and sharpener, an elongated body member having a longitudinal slot therein and cutting means along one margin of said slot, means for engaging the clip upon a pencil, said means serving also to assist in locating the point of the pencil for sharpening by said cutting means, and additional means along the opposite side of said slot from said cutting means for supporting the pencil point in proper cutting relation to said cutting means.

70 9. A pencil clip and sharpener of the character described comprising, in combination, an elongated body member having longitudinal cutting means thereon, means for connecting the

device to a pencil serving also to locate the point of the pencil with respect to said cutting means for sharpening, and means cooperating with said last mentioned means to assist in locating the pencil point in proper sharpening position relative to said cutting means.

10. A pencil clip and sharpening device of the character described comprising, in combination, a body member, a spring member, means cooperating with said spring member for connecting the device to a pencil, a knife blade, a series of connecting flanges and lugs for connecting said spring member and said knife blade to said body member in such relation that a pencil point may be inserted between said spring member and said body member to be sharpened by said knife blade, said series including flanges and lugs adjacent the respective opposite ends of said body member for limiting the outward flexing movement of said spring member when said device is being used as a pencil sharpener, and means for limiting the length of the pencil point.

11. A device of the character described comprising, in combination, an elongated body member having a longitudinal slot therein, a knife blade secured to said body member at one side of said slot for sharpening a pencil point, and a shoulder on said blade for engagement by said pencil point to limit the length of the latter.

12. A pencil clip and sharpening device of the character described comprising, in combination, an elongated body member having cutting means thereon, and a spring lever secured at one end to said body member and projecting divergently therefrom for retaining a pencil point in position to be sharpened by said cutting means, said spring lever having an escape opening for material shaved from the pencil point.

13. A pencil sharpening device including, in combination, a blade, a spring member and a body member cooperating with said blade to form a socket for receiving and properly locating a pencil point to be sharpened relative to the blade, said spring member having a bowed cross-section adjacent the sharpened lead tip providing a clearance space to avoid binding or jamming and breaking of the lead tip.

14. A pencil clip and sharpener device comprising, in combination, an elongated clip body having means adjacent to one end thereof for embracing a pencil, an elongated spring lever having one end thereof secured adjacent to the opposite end of said body member and extending freely opposite said one end of the body member

5 for cooperation with said pencil-engaging means in holding the device upon the pencil, an engagement nib at said opposite end of said body member beyond the end of said spring lever and arranged to be pressed against the body of the pencil or to grip the wall of a pocket upon which the assembled pencil and clip may be clipped, said spring lever being arranged to stand away from said one end of said clip body when the device is removed from the pencil whereupon the pencil point may be inserted into the space therebetween, and a knife edge located on said body for sharpening the pencil point after insertion of the latter into said space.

15. In combination in a pencil clip and sharpener device of the character described, an elongated body member, means on said body providing a knife edge for sharpening the point of a pencil, means adjacent to one end of the body member for embracing a pencil, spring means for assisting in such embracing of the pencil lying between said knife edge means and the embraced pencil, and a nib at the opposite end of the body member for gripping a pocket wall upon which the pencil and clip assembly may be carried, said body member and spring means being so related that by compressing the spring member said nib may be released from its gripping relation and in sharpening the pencil point the pencil must be removed from the device and the point inserted between said body and said spring means.

16. In a device of the character described, the combination of an elongated body member having a longitudinal slot therein, a knife blade secured to said body member at one side of said slot for sharpening a pencil point, a gauging flange extending along the opposite side of said slot for centering the tapered pencil point with respect to said knife edge, and means providing lateral support for said pencil point adjacent said gauging flange.

17. A device of the character described comprising, in combination, an elongated body member having a longitudinal slot therein, a knife blade secured to said body member at one side of said slot for sharpening a pencil point, means for supporting a pencil on said body member, and a gauging flange extending along the opposite side of said slot for centering the tapered pencil point relative to said knife edge.
